UNITED STATES PATENT OFFICE

170,149

TOY COMPASS

Lawrence E. Cooke, Houston, Tex.

Application May 3, 1952, Serial No. 19,575

Term of patent 3½ years

(Cl. D34—15)

To all whom it may concern:

Be it known that I, Lawrence E. Cooke, a citizen of the United States, residing at Houston, county of Harris and State of Texas, have invented a new, original, and ornamental Design for a Toy Compass, of which the following is a specification; reference being had to the accompanying drawing, forming part thereof.

Fig. 1 is a front elevational view of a toy compass showing my new design;

Fig. 2 is a side elevational view of the same, and

Fig. 3 is a rear elevational view of the same.
I claim:

The ornamental design for a toy compass, substantially as shown.

LAWRENCE E. COOKE.
